CLAIM

The ornamental design for a helmet as shown and described.

DESCRIPTION

FIG. 1 is a top-front-right perspective view of a helmet, showing our new design;

FIG. 2 is a front elevation view thereof;

FIG. 3 is a rear elevation view thereof;

FIG. 4 is a right side elevation view thereof; and,

FIG. 5 is a top plan view thereof.

The broken lines in the figures illustrate portions of the helmet that form no part of the claimed design.
